METRONOME

George C. Engel, Ridgewood, N. J., and Frank L. Eidmann, deceased, late of Princeton, N. J., by Ethel I. Eidmann, executrix, Princeton, N. J., assignors to General Time Instruments Corporation, New York, N. Y., a corporation of Delaware

Application April 11, 1942, Serial No. 438,622

11 Claims. (Cl. 58—130)

This invention relates to metronomes and in particular to an improved device for producing audible signals at regular intervals in order to facilitate the execution of musical compositions.

The audible signals produced by a metronome are commonly of two types: a series of beats which indicate the tempo of the music, for example 50 beats per minute; and a series of accents which indicate the rhythm of the music or the beginning of each measure. The accents are commonly sounded simultaneously with every second, third, fourth or sixth beat depending on whether the composition calls for 2/4, 3/4, 4/4 or 6/8 time, respectively.

It is a primary object of this invention to provide an improved electrically driven metronome which can be adjusted to produce a predetermined number of beats per minute, together with the desired accents.

A further object is to provide an improved variable speed transmission which is adapted for use in a metronome.

Another object is to provide improved accent sounding mechanism for a metronome which can be shifted from one kind of time or accent to another without stopping the metronome.

Still another object is to provide for a metronome an improved non-dampening bell striking mechanism.

It is also an object to provide a metronome of inexpensive and of simple construction which may be driven by the small amount of power produced by the usual electric clock motor.

Other objects, features and advantages will become apparent as the description proceeds.

In the drawings in which like reference numerals refer to like parts,

Fig. 1 is a front elevation of a preferred embodiment of this invention, the housing being removed;

Fig. 2 is a plan view of the device shown in Fig. 1;

Fig. 3 is a side elevation, partly in section, of the device shown in Figs. 1 and 2;

Fig. 4 is a section taken along line 4—4 of Fig. 3;

Fig. 5 is an enlarged section of a detail taken along line 5—5 of Fig. 3;

Fig. 6 is a section taken along line 6—6 of Fig. 3;

Fig. 7 is a section taken along line 7—7 of Fig. 3;

Fig. 8 is an enlarged section taken along line 8—8 of Fig. 4 showing certain details thereof;

Fig. 9 is an enlarged plan view taken along line 9—9 of Fig. 8;

Figs. 10, 11 and 12 are sections taken along lines 10—10, 11—11 and 12—12 of Fig. 8, showing the different shapes of cams provided; and,

Fig. 13 is a detailed view of the framework for supporting the splined shaft, the friction wheel and other parts being omitted for the purpose of clarity.

Referring now to Figs. 1 to 4 which show the general relationship of the parts, the mechanism is mounted on a base 15, and driven by a self-starting synchronous electric motor 16 which is screwed to the underside of the base. A slotted plate 17 is suitably secured to the front edge of the base in perpendicular relationship thereto, and as shown in Fig. 1, it is provided with a slot 53 through which a manually operated knob 43 extends. A plate 93 is also provided at the front edge of the base and extends downwardly therefrom, and a rotatable knob 95 is journaled in this plate 93.

Secured to the base 15 are side members 18 and 19 which extend upwardly and inwardly and which are associated with each other at their upper ends by an L-shaped strip 20 which strip is also secured to the upper portion of the slotted plate 17. The above mentioned parts may be screwed to each other in order to form a rigid structure.

A driving pinion 21 is secured to the drive shaft of the motor which extends through the base 15, the pinion being disposed on the upper surface of the base. A gear 22 is mounted on a shaft 23 which is journaled in the base 15 and in the L-shaped strip 20, the gear 22 meshing with the pinion 21 so that the shaft 23 will be rotated thereby. A conically shaped hard rubber driving member 24 is mounted on the shaft 23. The base 15 is bent so that the shaft 23 is disposed at an angle to the slotted plate 17 and so that a line drawn vertically along the surface of the cone 24, at that point on the surface which is nearest the slotted plate, will be parallel thereto. The cone forms one element of a variable speed transmission, the other element of which is a friction wheel 25 which is mounted on a splined shaft 26 in axially shiftable relationship, but which friction wheel is constrained to rotate with the shaft by virtue of the spline 27 which cooperates with a corresponding key on the friction wheel. The splined shaft 26 is rotatably mounted in a frame designated generally by the reference numeral 28, the framework being pivotally mounted so that the shaft may

be moved bodily toward and away from the surface of the cone 24. As shown in Fig. 13, the framework comprises a vertical member 29 to the lower end of which is secured a horizontal member 30. The upper end of the vertical member 29 is received in and pinned to a socket 31 which forms a part of an upper horizontally disposed member 32. The reduced ends of the shaft 26 are received in and journalled in the horizontal members 30 and 32. The framework 28 is pivotally mounted in the base 15 and in a bracket 33 which bracket is formed by a forwardly and upwardly extending portion of the L-shaped strip 20, the reduced ends of the vertical member 29 extending through the horizontal members 30 and 32 and being received in apertures provided in the base 15 and in the bracket 33 for that purpose. A pin 34 extends upwardly from the bracket 33 and is engaged by a leaf spring 35 which is anchored by a screw 36 to the upper surface of the bracket 33 so that the framework 28 as a whole and the friction wheel 25 will be biased against the surface of the cone 24.

The friction wheel 25 as shown in Fig. 8 comprises a hub member 37 which is provided with two flanges 38, a rubber tire or ring 39 being held between the flanges and extending outwardly beyond the same for engagement with the surface of the cone 24. An annular groove 40 is provided in the upper portion of the hub member 37 and is adapted to receive the spherically shaped end 41 of the manually operable sliding member which is generally designated by the reference numeral 42.

As shown in Fig. 5 the sliding member 42 consists essentially of a bar which has been turned so that its forward end forms the above mentioned knob 43, and so that it is also provided with an intermediate portion 44 of reduced diameter. The intermediate portion 44 is provided with screw-threads 46 upon which a nut 47 is disposed. A diamond shaped plate which serves as a pointer 48 and a spring plate 49 are also disposed on the intermediate portion 44, and together with a collar 50 and with the washers 51 and 52, are confined between the knob 43 and the nut 47. The collar 50 slides in the slot 53, and the front and rear surfaces of the plate 17 are engaged by the pointer 48 and the spring plate 49, the whole assembly being secured together for a minimum amount of play so that for any given position of the sliding member 42, the friction wheel 25 will engage the cone 24 at a predetermined point. The plate 17 is provided on its rear surface with a series of depressions 54 which are engaged by projections 55 which are stamped in the spring plate 49 in order that the position of the sliding member 42 may be fixed. Indicia 56 are stamped on the front surface of the slotted plate 17 which indicate the number of revolutions per minute of the friction wheel 25 when held in the vertical position indicated.

The beats are produced by a hammer 60 which strikes a sounding board 61 which is suitably secured to the side member 18. The sounding board may be of any suitable material such as a reenforced sheet of phenol formaldehyde condensation product. The hammer 60 is actuated once for each revolution of the splined shaft 26 so that the indicia 56 will indicate not only the speed of the shaft but also the tempo or number of beats per minute.

The hammer 60 is mounted on an arm 65, the arm being secured to a hub member 62 which is rotatably journalled on the lower horizontal

member 30. The forward end of the arm 65 is engaged by a cam 63 which is secured to the lower portion of the spline shaft 26. A spring 66 extends between the arm 65 and a pin 67 which is mounted on the base 15. It will be seen that the spring biases the forward end of the arm 65 against the cam 63, and the hammer 60 against the sounding board 61. As the cam rotates, the hammer is withdrawn from the sounding board 61 against the bias of the spring 66, until the drop face of the cam is rotated past the end of the arm 65, at which time the spring causes the hammer to strike the board to sound a beat. The spring 66 also cooperates with the leaf spring 35 to urge the friction wheel 25 against the cone 24.

The accent is indicated by a hammer 70 which strikes a bell 71, the bell being suitably secured to the side member 19 as shown in Fig. 4. The hammer 70 is mounted upon an arm 72, the arm being secured to an arbor 73 which is journalled in the base 15 and in a plate 74, the latter plate being mounted above the base and spaced therefrom by means of spacers 75. The hammer is driven from the splined shaft 26 by means which include a single toothed wheel 76 which is secured to the shaft 26 at a point beneath the cam 63. A star wheel 77, mounted on a shaft 78 journalled in the base 15 and the plate 74, is engaged by the single toothed wheel 76, and rotated to the extent of one tooth for each complete revolution of the splined shaft 26.

A sleeve 79 is mounted on the shaft 78 in axially shiftable relationship thereto, and is provided with a plurality of cams 80, 81, 82 and 83, each of which cams is provided with a plurality of drops. As shown in Figs. 9 to 12 inclusive, the cam 80 has two drop surfaces, and the cams 81, 82 and 83 have 3, 4 and 6 drop surfaces respectively. The sleeve 79 is keyed to the shaft 78 by means of a key 84 so that the cams will be rotated with the star wheel 77. A coil spring 85 surrounds the shaft 78 and serves to urge the sleeve 79 and its associated cams downwardly against the star wheel as shown in Fig. 8.

A rider 86 is provided for selectively engaging one or the other of the cams 80—83, the rider being secured to a rock shaft 87 which is journalled in the base 15 and the plate 74. An upper collar 88 and a lower collar 89 are secured to the rock shaft 87, and as shown in Fig. 8 a coil spring 90 is disposed on the rock shaft 87 and is confined between the lower collar 89 and the plate 74 so as to urge the rock shaft downwardly to the limit of its motion as determined by the engagement of the upper collar 86 by the plate 74. The rock shaft 87 is slidably mounted in the base 15 and in the plate 74. In this neutral position of the parts, as shown in solid lines in Fig. 8, the rider 86 clears the cams so that the hammer 70 is not operated. The vertical position of the rock shaft 87 is determined by a cam 91 which engages the lower end thereof.

A U-shaped bar 96 is secured to the collars 88 and 89, the intermediate portion of which bar is disposed parallel to the rock shaft 87, and extends through an aperture 100 in the plate 74. A spring 97 is tensioned between the U-shaped bar 96 and a pin 98, the pin being mounted in the plate 74. The spring 97 biases the cam rider against one or the other of the cams 80—83, and also maintains the U-shaped bar in engagement with the arm 72 of the hammer 70. The bar 96 and the rider 86 may be constructed from a single piece of bar stock as shown in Figs. 8 and 9.

A coil spring 99 is provided for the arbor 73

to bias the hammer 70 away from the bell and to maintain the other end of the arm 72 in engagement with the U-shaped bar 96. The tension of this coil spring 99 is less than the tension of the spring 91. When the rock shaft 87 is maintained in elevated position so that the rider 86 engages one of the cams, it will be seen that each time the rider drops off of a drop face, that the bar 96 will engage and rotate the arm 72. The inertia of the hammer 70 and of the arm will cause the arm to be rotated in the counterclockwise direction beyond the solid line position shown in Fig. 9 so that the hammer will strike the bell as shown by the broken lines. The rebound of the hammer from the bell will be aided by the coil spring 99 which will also serve to maintain the hammer away from the bell so that the tone of the bell will not be damped.

The cam 91 is secured to a shaft 92 which shaft is journalled in the plate 93 and in a U-shaped bracket 94, the bracket being secured to the underside of the base 15. The knob 95 is secured to the shaft 92 forwardly of the plate 93, and a spring arm 101 is secured to the rear end of the shaft 92. As shown in Figs. 7 and 8 the rear half of the U-shaped bracket 94 is provided with a series of apertures 103, and the spring arm 101 is provided with a projection 102 which is adapted to engage one or the other of the apertures 103 to maintain the cam 91 in a predetermined position. As shown in Fig. 1 the plate 93 is provided on its front surface with the numerals "2," "3," "4" and "6," each one of which numerals corresponds with one of the apertures 103. When the knob is rotated so that the arrow on the knob points to one of the numerals, the cam will cause the rock shaft 87 to be elevated so that the rider 86 engages the corresponding cam. When the arrow points to "2," cam 83 will be engaged. Cam 83 has six teeth which will result in the accent being sounded every second beat, inasmuch as the star wheel is provided with twelve teeth. Similarly when the pointer on knob 95 points to "3," "4" or "6," the accent will be sounded on every third, fourth or sixth beat.

The circuit to the motor 16 is opened and closed by rotating the knob 95. A stationary contact 104 is secured to an insulating strip 105 mounted on the upper surface of the base 15 as shown in Figs. 6 and 7. A resilient contact member 106 is also secured to the insulating strip 105, and is biased downwardly to make contact with the stationary contact 104. An insulating rod 107 is vertically and slidably disposed in the base 15 and in the connecting portion of the U-shaped bracket 94, and is provided with an enlarged portion at its upper end which prevents it from dropping through the base 15 through which it extends. The upper portion of the insulating rod 107 engages the resilient contact member 106 and the lower end of the rod is engaged by a radially disposed face 108 provided on the cam 91. It will be seen that as the knob 95 is rotated to the limit of its rotation, as determined by the stop 109 the insulating rod 107 will be pushed upwardly, thereby opening the circuit between the contacts 104 and 106. The series of apertures 103 includes an aperture which serves to maintain the insulating rod 107 in its elevated position against the bias of the resilient contact member 106. Conductors 110 and 111 extend from the contact members to the motor.

As shown in Fig. 1, the knob 95 is in the open circuit position, and the metronome is inoperative. To operate the metronome, the knob 95

is rotated in the clockwise direction to its "on" position, thereby permitting the contact 106 to drop and to close the motor circuit. The beat hammer 60 will then be operated by the cam 63 to produce a given number of beats per minute, as indicated by the cooperation of the pointer 48 with the indicia 56. The tempo may be varied by shifting the position of the sliding knob 43.

In this position of the parts (i. e., when the arrow on the knob 95 points to "on") the accent is not sounded because the rider 86 is maintained clear of the cams 80 to 83, as shown in Fig. 8. If it is desired to operate the accent sounding mechanism for 4/4 time, the knob 95 is rotated to its "4" position. This causes the rock shaft 87 and the rider 86 to be elevated to a position wherein the rider will be opposite the cam 81. In the event that the position of the lowermost cam 83 tends to block the shifting of the rider, the whole group of cams will be elevated with the rider against the bias of spring 85. This position of the parts is shown in broken lines in Fig. 8. Subsequent rotation of the cams will permit the spring 85 to force the group downwardly, step by step, to the normal solid line position, after which the accent will be sounded on every fourth beat as desired.

The rider 86 may be shifted downwardly by rotating the knob 95 and the cam 91. In case an adjacent cam blocks the downward movement, the action will be delayed, but the spring 90 will cause a step by step downward movement during the subsequent revolution of the group of cams. The axially shiftable mounting of the cams and of the rider permits the manual setting of the knob 95 at any time.

As shown in Fig. 9, the parts are adjusted for an accent on every sixth beat, the cam 80 having two drop surfaces.

The non-dampening operation of the accent hammer 70 and the operation of the beat hammer 60 have been described above. The parts are preferably timed so that the accent is produced simultaneously with a beat, this timing being effected at the factory by adjusting the angular position of the cam 63 with respect to the single toothed wheel 76.

It will be obvious to those skilled in the art that various modifications and changes in the size, shape and proportion of the parts may be effected without departing from the spirit of this invention. The above description relates to a preferred embodiment only and is not intended to limit the scope of this invention which is defined in the appended claims.

What is claimed as new is:

1. A metronome comprising constant speed driving means, a conical friction element driven thereby, a pivotally mounted frame adjacent said conical friction element, a shaft journalled in said frame, a friction wheel mounted on said shaft for cooperation with said conical friction element, a cam associated with said shaft and a striker arm actuated by said cam, said striker arm being pivotally mounted on said frame, and a spring tensioned between said striker arm and a fixed point so as to urge the end of said striker arm against said cam and the periphery of said cooperating friction wheel against the surface of said conical friction element.

2. A metronome comprising a pivotally mounted beat hammer and a pivotally mounted accent hammer, cam means for actuating said beat hammer and cam means for driving said accent hammer, and variable speed driving means

for each of said cam means, said last mentioned cam means comprising a series of co-axially secured cams, a cam rider for cooperation with one of said cams, means to shift the position of said cam rider so that it will selectively engage one or the other of said cams, said cams being axially shiftable so as to permit displacement thereof by said rider when an adjacent cam blocks the free axial movement of said rider from one cam face to the next, and a spring for shifting said cams back to their original position when said adjacent cam has been rotated to an extent so as to permit relative movement of said rider and of said cams.

3. A metronome comprising a pivotally mounted beat hammer and a pivotally mounted accent hammer, cam means for actuating said beat hammer and cam means for driving said accent hammer, said last mentioned cam means comprising a group of co-axially arranged cams, an axially displaceable rock shaft, a cam rider for selective cooperation with one or the other of the cams of said group, said cam rider being secured to said axially displaceable rock shaft, control means engaging said rock shaft to shift its axial position upwardly, and a spring engaging said rock shaft for urging the same downwardly against said control means, whereby the downward movement of said cam rider from one cam to another subsequent to the operation of said control means may be delayed until such time as said rider is not blocked by the projecting portion of an adjacent cam.

4. In a metronome having an accent hammer, means for actuating said accent hammer at variable intervals, said means including a cam shaft, a plurality of cams keyed to said shaft in axially shiftable relationship, stop means secured to said shaft for limiting the movement of said cams in the downward direction, a displaceable rider for selectively engaging one or the other of said cams, second stop means for limiting the movement of said rider in the downward direction, means for adjusting the position of said second mentioned stop means, the positions of said rider and of said cams with respect to each other during and after the operation of said adjusting means remaining the same when the relative motion of one with respect to the other is blocked by the projecting portion of an adjacent cam, and separate means to urge said rider and said cams against their respective stop members so that the positions of said rider and of said cams may be shifted with respect to each other when said adjacent cam has been rotated so as to clear said rider, and means for rotating said cam shaft.

5. In a metronome having a bell and a pivotally mounted hammer for said bell, a cam rider adapted to contact said hammer, means to bias said hammer into contact with said cam rider, a group of cams cooperating with said cam rider, a spring for urging said cam rider into contact with one or the other of the cams of said group, said spring being stronger than said hammer biasing means so that as said rider drops off of one of said cams, a quick operative stroke will be imparted to said hammer, said cams each being provided with a different number of drop surfaces, and means to adjust the axial position of said rider with respect to said cams so as to determine the frequency with which said hammer strikes said bell, depending upon the number of drop surfaces of the particular cam engaged by said rider in its adjusted position.

6. A metronome comprising a synchronous

electric motor, a variable speed transmission device associated therewith, a beat hammer and an accent hammer driven by said variable speed transmission device, means to adjust the operation of said accent hammer, a switch for said motor, and common control means for said motor switch and for said adjusting means.

7. A metronome comprising a synchronous electric motor, variable speed transmission means associated therewith, a beat hammer and an accent hammer driven by said variable speed transmission means, manually rotatable means for regulating the frequency of operation of said accent hammer, a switch for said motor, and an actuating member associated with said switch and extending into the path of said manually rotatable means, the parts being so constructed that when said manually rotatable member is rotated in one direction from a neutral position, said motor switch is opened, and when rotated in the opposite direction from said neutral position, the frequency of operation of said accent hammer is regulated.

8. In a metronome having an accent hammer, a group of cams, a cam rider selectively cooperating with one or the other of the cams of said group to control the operation of said accent hammer, a control cam for adjusting the position of said cam rider with respect to said group of cams, said control cam being provided with a radially extending face, an electric clock motor for driving said group of cams, and switch means for said motor including a switch actuating member extending into the path of said radially extending face.

9. In a metronome having an accent hammer, a group of cams, a cam rider selectively cooperating with one or the other of the cams of said group to control the operation of said accent hammer, a control cam for adjusting the position of said cam rider with respect to said group of cams, said control cam being provided with a radially extending face, an electric clock motor for driving said group of cams, a switch for said motor, a switch actuating member extending into the path of said radially extending face whereby rotation of said control cam will cause said motor switch to be opened, and means to maintain said control cam in one or the other of a plurality of predetermined positions corresponding to those positions in which said rider engages one or the other of said cams, and in that position in which said radially extending face maintains said motor switch in open circuit position.

10. A metronome comprising time responsive driving means, a cone driven thereby at a constant rate of speed, a splined shaft spaced from said cone and substantially parallel to an adjacent portion of the surface thereof, a friction wheel mounted on said splined shaft in axially shiftable relationship and engaging the surface of said cone, and means to shift the position of said friction wheel along said splined shaft to regulate the speed of rotation of said splined shaft, said means including a slotted plate disposed parallel to said splined shaft, and a sliding member extending through said slotted plate and engaging said friction wheel, said sliding member being provided with plates embracing the opposite surfaces of said slotted plate, one of said surfaces being provided with a series of depressions, whereby one of said plates may selectively engage one or the other of said depressions to maintain said sliding member in a predetermined position.

11. A metronome comprising time responsive driving means, a cone driven thereby at a constant rate of speed, a shaft spaced from said cone, a friction wheel secured to said shaft in axially shiftable relationship thereto and engaging the surface of said cone, a slotted plate spaced from said shaft, a sliding member extending through said slotted plate and engaging said friction wheel to shift the axial position thereof, two plates secured to said sliding member and

resiliently embracing the opposite surfaces of said slotted plate, and signal producing means driven by said shaft for operation at regular intervals as determined by the speed of said shaft and the setting of said sliding member.
